COOKING RANGE

Albert E. Smallwood, Taunton, Mass., assignor to
 Servel, Inc., New York, N. Y., a corporation of
 Delaware

Application December 30, 1944, Serial No. 570,688

2 Claims. (Cl. 126—191)

1

My invention relates to cooking ranges, more particularly to oven and broiler doors for cooking ranges. More specifically, my invention relates to an intermediate stop or latch mechanism for oven and broiler doors.

Some of the advantages of having an intermediate latch mechanism on oven and broiler doors are that either, or both, of the oven or broiler doors may be held in slightly open or ajar position on heating up the desired section to permit the escape of excess moist air, thereby reducing condensation; it may be used for room heating purposes without having the open doors protruding appreciably into the room; and it may also be used for ventilating the broiler during broiling operations.

It is an object of my invention to provide an improved latch mechanism for oven and broiler doors that is quiet and positive in operation.

My invention, together with its objects and advantages, is more fully set forth in the following description and accompanying drawings, wherein like reference characters are used to designate like parts throughout the several views, and wherein:

Fig. 1 is a fragmentary sectional view of one end of a cooking range illustrating a door latch mechanism in accordance with my invention;

Fig. 2 is a sectional view taken substantially on line 2—2 of Fig. 1;

Fig. 3 is a fragmentary sectional view similar to Fig. 1, but to a larger scale and showing the door held in ajar position; and

Fig. 4 is an enlarged detail view of a spring shackle incorporating my invention.

Referring now to the drawings wherein I have illustrated my invention applied to the lower front outside corner of a cooking range oven or broiler. A duplicate mechanism (not shown) is applied to the opposite or lower front inside corner of the oven or broiler. As shown, the range includes an oven 10 provided with an outside wall 11, a door frame 12 and a door 13. Door 13 is attached to a door frame in any suitable manner, as by means of a pair of brackets 14 (only one of which is shown) which are welded or otherwise secured to the door frame. Bracket 14, which is generally U-shaped in cross-section, is provided with a guide pin 15. A flat metal strip 16 is welded or otherwise secured to a channel member 17, which forms part of the door structure, and is provided with a slot 18 in its lower end. Slot 18 is adapted to receive and cooperate with guide pin 15 in supporting the oven door on the door frame. Oven wall 11 in-

2

cludes an inner panel 20 and an outer panel 21, with insulating material 22 located therebetween. A sheet metal box or housing 23, located in the lower front corner of wall 11, provides a chamber 5 and support for the latch mechanism. Housing 23 also serves to hold the insulation in place between the wall panels.

My improved latch mechanism includes a bifurcated or U-shaped bracket 24 bolted or otherwise secured to housing 23 and provided with an opening in the outer end of each of its forks. A lever arm 25, generally U-shaped in cross-section, is pivotally mounted intermediate its ends on a pivot pin 26 which extends through the 15 openings in bracket 24. Lever arm 25 is provided on its upper end with projections 25a and 25b having openings in the ends thereof which are adapted to receive a journal pin 27. A ball-bearing roller 28 is mounted on journal pin 27 between projections 25a and 25b of lever arm 25. A spring shackle 29, mounted on journal pin 27, is provided with a cupped portion 30 adapted to receive one end of a compression spring 31. The opposite end of compression spring 31 is housed 25 in a spring barrel or well 32. An adjusting screw 33 is provided in the lower end of lever arm 25 to limit the outward movement of the upper end of said arm. A shock-absorbing leaf spring 34 functions as a yieldable stop for adjusting screw 30 33.

A bracket 35, formed of a pair of arms 35a and 35b joined by an arcuate portion 35c, is welded or otherwise secured to the oven door 13, as by welding arm 35a to channel member 17. The 35 arcuate portion 35c of the bracket passes into housing 23 through an elongate slot 36 provided in the door frame 12. Bracket arm 35b is provided with a straight portion 37, and convex cam surfaces 38 and 39 joined by a concave cam surface or recess 40. A counter-balancing tension spring 41 is connected at its upper end to bracket arm 35b by means of a stirrup or shackle 42, and at its lower end this tension spring is connected to an adjustable hook bolt 43. Stirrup 42 is pivotally mounted on bracket arm 35b by a pivot pin 44 in such manner that the stirrup pivots about this pin and there is substantially no movement between the stirrup and the upper looped end of tension spring 41. This arrangement 50 eliminates squeaking noises which are often caused by friction of a spring wire on a bracket arm when the spring is connected directly to the arm. Door 13 is provided with a suitable handle 45 whereby it may be conveniently moved between its open and closed position. A suitable

stop plate 46 is provided above slot 36 and is adapted to be engaged by the straight portion 37 of bracket arm 35b to limit the downward movement of door 13, as shown in broken lines in Fig. 1.

In operation, when the door is in closed position, as shown in Fig. 1, compression spring 31 holds roller 28 against cam surface 38 of bracket arm 35b, thereby holding the door in closed position. Tension spring 41 also assists in holding the door in its closed position. It is to be understood that while springs 31 and 41 are sufficiently strong to positively hold the door in its closed position, they will not unduly hinder movement of the door toward its open position when such movement is desired. When it is desired to open the door the handle 45 is grasped and the door is moved outward and downward about the pin and slot supports at its lower edge. The cam surface 38 of bracket arm 35b rides over roller 28 and said roller engages the concave or recessed portion 40 at which time the motion of the door will be retarded, and unless additional force is applied to the door handle the door will be held in this ajar position, as shown in Fig. 3, by the action of compression spring 31. However, should additional force be applied to the door handle, the recessed portion 40 of bracket arm 35b leaves the roller 28 and cam surface 39 passes over and finally leaves the roller, during which movement, the tension on counter-balance spring 41 is increased and counterbalances the door during its downward movement. As cam surface 39 leaves roller 28 outward movement of lever arm 25 is limited by adjusting screw 33 which contacts shock-absorbing spring 34. By this arrangement, roller 28 is positioned to receive cam surface 39 when the door again approaches its closed position. Downward movement of the door is continued until the straight portion 37 of bracket arm 35b contacts stop plate 46 at which time the door will have reached its horizontal or fully open position, as shown in broken lines in Fig. 1. In closing the door the operation is reversed. That is, the door is moved upward, aided by the tension on counter-balance spring 41, and cam surface 39 again contacts and rides over roller 28. From cam surface 39 the roller engages the recessed portion 40 of bracket arm 35b, thereby retarding the upward motion of the door unless additional force is applied thereto. In other words, the door is again held in ajar position by compression spring 31. When it is desired to fully close the door, it is merely necessary to apply an additional force thereto which will cause cam surface 38 to ride upon the roller so as to hold the door closed, as shown in Fig. 1.

While I have illustrated and described one specific embodiment of my invention, it obviously

may take other forms and be variously applied within the scope of the following claims.

What I claim is:

1. In a cooking range, an oven provided with insulated walls forming a cooking chamber having a front opening therein, a door frame surrounding said opening, a door supported on said frame for closing said opening, latch mechanism for holding said door in different positions, relative to said opening, said latch mechanism including a housing positioned between said insulated walls, a bracket supported in said housing, a lever arm pivotally supported by said bracket, a roller journaled on one side of said lever arm, a compression spring mounted on the opposite side of said lever arm in horizontal alignment with said roller for biasing said lever arm and roller toward said door, a second bracket rigidly connected to said door, said second bracket including an arm projecting into said housing, said arm having a plurality of cam surfaces on its inner end adapted to engage said roller, the construction and arrangement being such that said spring urges said roller into engagement with one of said cam surfaces to hold said door in closed position and into engagement with another of said cam surfaces to hold said door in ajar position.
2. In a cooking range, an oven provided with insulated walls forming a heating chamber having a front opening therein, a frame surrounding said opening, a door supported on said frame for movement between a vertical closed position and a horizontal open position, latch mechanism for holding said door in different positions, said latch mechanism including a housing positioned between said insulated walls, a bracket supported in said housing, a lever arm pivotally supported by said bracket, a roller journaled on one end of said lever arm at one side thereof, a compression spring mounted on the opposite side of said lever arm in horizontal alignment with said roller for biasing said lever arm and roller toward said door, a second bracket rigidly connected to said door, said second bracket including an arm projecting into said housing, said arm being provided with a plurality of convex cam surfaces separated by an immediately adjacent arcuate recess, and said arm also being provided with a straight portion substantially perpendicular to the plane of said door, the construction and arrangement being such that said spring urges said roller into contact with one of said convex cam surfaces to hold said door in closed position and with said arcuate recess to hold said door in ajar position, and said straight portion contacts said frame to limit the movement of said door toward open position.

ALBERT E. SMALLWOOD.
